UNITED STATES PATENT OFFICE.

GEORGE C. ANDREWS, OF MINNEAPOLIS, MINNESOTA.

WATER-INTAKE VALVE AND SAFETY DEVICE FOR HOT-WATER HEATING SYSTEMS.

No. 909,857.

Specification of Letters Patent.

Patented Jan. 19, 1909.

Application filed March 13, 1908. Serial No. 420,866.

To all whom it may concern:

Be it known that I, GEORGE C. ANDREWS, a citizen of the United States, residing at Minneapolis, in the county of Hennepin and State of Minnesota, have invented certain new and useful Improvements in Water-Intake Valves and Safety Devices for Hot-Water Heating Systems; and I do hereby declare the following to be a full, clear, and exact description of the invention, such as will enable others skilled in the art to which it appertains to make and use the same:

My invention has for its object to provide an improved safety valve mechanism especially adapted for use in connection with hot water and steam heating systems; and to the above ends the invention consists of the novel devices and combinations of devices herein-after described and defined in the claims.

20 The invention is illustrated in the accompanying drawings, wherein like characters indicate like parts throughout the several views.

25 Referring to the drawings, Figure 1 is a view chiefly in vertical section, but with some parts in full elevation and some parts broken away, illustrating my improved valve mechanism; and Fig. 2 is a fragmentary view in vertical section, illustrating a modified 30 form of the valve mechanism.

Referring first to the construction illustrated in Fig. 1, the numeral 1 indicates the main body portion of the valve mechanism, the same, as shown, being integrally connected, by a neck portion 2, to a laterally offset supplemental casing 3. This valve mechanism will usually be placed in the water supply tank of a hot water heating system; and the lower end of the casing 1 is adapted 35 to be screwed onto the upper end of a water pipe or stack 4. The extreme upper end of the casing 1 is shown as closed by a threaded plug 5 below which are lateral escape passages 6. Just below the escape passages 6 the 40 casing 1 is provided with an internal annular valve seat 7 upon which normally rests a safety valve 8, the stem 9 of which works upward through the plug 5 and is secured, at its upper end, to a weight 10. This weight 45 10 should be such that the valve 8 will be held in a closed position or seated against the valve seat 7 under all normal pressures which it is desired to maintain within the 50 circulating connections of the heating system, but should be such that under abnormal pressures, such as might produce undue

strains on the pipes or radiators or the boiler, said valve will be forced open, thereby permitting an escape of steam through the passages 6. This valve, therefore, works 60 automatically to prevent excessive pressures within the heating system and no other safety device would be required were it not for the fact that there is a slight possibility that said valve may sometime become stuck 65 by corrosion or by an accumulation of sediment and thereby rendered inoperative as a safety device. I have, therefore, provided an auxiliary safety device which can in no wise be rendered inoperative by corrosion 70 or by any other thing that could accidentally occur thereto. This supplemental safety device is in the nature of a disk, plate or sheet of imperforate material which, under all normal pressures in the system, will remain intact and keep closed the blow-off or escape passage, but which, under predetermined abnormal or excessive pressure, will break or give way and thereby open up 75 said escape passage and permit the steam 80 from the system to escape. In the construction illustrated in Fig. 1, this safety disk or plate 11 is clamped with a steam-tight joint in the upper end of the supplemental casing 3 by means of a cap nut or 85 cage 12 which, as shown, has a multiplicity of discharge passages 13. This safety plate 11 may be constructed of thin metal, of vulcanized rubber or any other suitable material which will not rapidly deteriorate under the 90 action of water and steam and which will have the required strength to resist normal pressures from the system. When used in connection with the weighted or supplemental safety valve it should have such 95 strength that it will remain intact and resist pressures which will open the said primary safety valve. Such an arrangement will give the safety valve a chance to open up to 100 perform all of the work of preventing excessive or dangerous pressures in the system; and the said safety valve will perform these functions unless, as may possibly happen in some rare instances, it becomes stuck by 105 corrosion or locked by sediment, in which case the said safety plate will, under slightly greater internal pressure of the system, give way and thus prevent accidents due to explosions. This, as is evident, is a very desirable arrangement because the safety valve 110 8 will become again closed and keep the system in good running condition following

each time that it happens to open to relieve pressure; whereas when the safety plate 11 is blown out it will be necessary to replace the same before the system will be again put 5 under normal running condition.

In connection with valve mechanism of this character, an automatic water intake valve is provided; and this valve is preferably in the 10 form of a gravity seated ball 14 that normally closes an intake port 15 formed in the bottom of the supplemental case 3. In practice the entire valve mechanism shown will be submerged in the water supply tank; and, if desired, there may be provided a float 16 15 having a stem 17 arranged to bear against the lower portion of said ball valve 14. This stem 17 may be guided for vertical movements in any suitable way, as, for instance, by a spider bracket 18 secured to the bottom 20 of the supplemental case 3. This float 16 should have such buoyancy that it will assist in unseating the valve 14, but will not in itself raise the said valve from its seated position. The purpose of this float would 25 be to assist in opening the valve 14 when the pressure within the system, due to condensation of steam or contraction of the hot water, is less than atmospheric pressure, so as to thereby cause the intake valve to open up 30 and permit inflow of water to replenish or keep up the water supply in the system.

In the construction illustrated in Fig. 2, the upper end of the supplemental casing 3 is permanently closed by a removable plug 35 19 and the ball valve which normally closes the water inlet port 15 is made in two parts, connected by screw-threaded engagement and clamping between its sections a safety disk or plate 11. Also the sections 20 of this two- 40 part ball valve are formed with axial passages 20^a and the upper ball section is provided with upwardly projecting fingers 20^b that are adapted to engage the interior of the casing 3 and thereby prevent the ball 45 valve from turning into a position in which

the lower passage 20^a will be out of registration with the port 15.

With the ball valve shown in Fig. 2, the pocket formed by the lower passage 20^a will never be entirely filled with water but will 50 contain more or less air which serves as a float to partly sustain the weight of said inlet valve.

As already indicated, in both of the constructions described, the so-called safety plate 55 or disk, when it is blown out or broken by excessive pressure, will permit the escape of steam from the heating system and thus absolutely protect the system from the disastrous effect of very high pressure. 60

The safety plate 11 might, in some instances, be formed integral with the cap 12; and, in other instances, it might be applied to the safety valve 8. 65

What I claim is:

1. In a valve mechanism of the kind described, the combination with a casing, of a normally closed water inlet valve adapted to be opened by external pressure in excess of the internal pressure, of a safety plate adapted 70 to be blown out by excessive pressure from within said casing, substantially as described.

2. In a valve mechanism of the kind described, the combination with a casing, of a normally closed water inlet valve adapted to be opened up by external pressure in excess of that of the internal pressure, of a yieldingly closed safety valve adapted to be opened by a predetermined internal pressure, and a safety plate adapted to be blown out by internal pressure in excess of that under which said safety valve is set to open, substantially as described. 75 80

In testimony whereof I affix my signature in presence of two witnesses.

GEORGE C. ANDREWS.
